OTHER PUBLICATIONS

File History of U.S. Appl. No. 29/514,538, filed Jan. 13, 2015, priority date Dec. 4, 2009, entitled Hub for Motorized Wheel.

(Continued)

Primary Examiner — George D. Kirschbaum*(74) Attorney, Agent, or Firm* — GTC Law Group PC & Affiliates(57) **CLAIM**

The ornamental design for a multiple speed motorized wheel hub, as shown and described.

DESCRIPTION

FIG. 1 is a perspective view of the left, drive side, of the multiple speed motorized wheel hub attached to a bicycle; FIG. 2 is a left, drive side, plan view of the multiple speed motorized wheel hub;

FIG. 3 is a front view of the multiple speed motorized wheel hub;

FIG. 4 is a right, non-drive, side plan view of the multiple speed motorized wheel hub; and,

FIG. 5 is a perspective view of the right, non-drive, side of the multiple speed motorized wheel hub attached to a bicycle.

In the drawings, the broken lines depict environmental subject matter only and form no part of the claimed design.

1 Claim, 5 Drawing Sheets(56)
